WALL MOUNTED REFRIGERATOR

Robert E. Munz, Jeffersontown, and William F. Saenger,
Louisville, Ky., assignors to General Electric Company,
a corporation of New York

Application November 29, 1955, Serial No. 39,084

Term of patent 14 years

(Cl. D67—3)

FIG. 1

FIG. 2

Figure 1 is a perspective view of a wall mounted refrigerator embodying our new design; and

Figure 2 is a second perspective view of said wall mounted refrigerator showing the interior thereof.

The right side of the wall mounted refrigerator is the same as the left side illustrated in Figure 1 of the drawing.

We claim:

The ornamental design for a wall mounted refrigerator, substantially as shown and described.
